United States Patent Office.

PERLEY H. LAWRENCE, OF PETROLEUM CENTRE, PENNSYLVANIA.

Letters Patent No. 105,156, dated July 5, 1870.

IMPROVEMENT IN APPARATUS FOR CUTTING THE CASINGS OR TUBES OF OIL-WELLS.

The Schedule referred to in these Letters Patent and making part of the same.

To all whom it may concern:

Be it known that I, PERLEY H. LAWRENCE, of Petroleum Centre, in the county of Venango and State of Pennsylvania, have invented certain new and useful Improvements in a Casing-Cutter, or an Apparatus for Relieving the Tubing in Oil-Well; and the following is a full, clear, and exact description of the same, reference being had to the accompanying drawing making a part of this specification, in which—

Figure 1 represents an exterior view of the apparatus, showing the cutting-tool or spur protruding through the surface.

Figure 2 shows a longitudinal sectional view through the same at the line *w w*.

Figure 3 shows a cross-sectional view through at the line *x x*.

Figure 4 is an end or cross-sectional view at the line *y y*.

Figure 5 represents the interior plug, with an inclined groove, to operate the cutting-tool or spur and the connecting-rod.

Figure 6 shows the lower end view of the plug or sliding wedge.

The object of my invention is to cut the casing or tubing in oil-wells, so as to relieve them from the seed-bag water-packers, or other obstructions; and

It consists of a revolving head or tool-holder, provided with one or more cutting-tools or spurs, so fitted in the stock or head that it or they may be forced out by the action of an inclined groove, made longitudinally in a plug fitted to slide up or down in the stock.

The plug being connected with and is operated by a small pipe or rod from the top, it being put down in the casing to the point desired to be cut.

To enable others to make and use my invention I will describe it more in detail, referring to the drawing and to the letters of reference marked thereon.

The head or stock A may be made of cast metal of any required size, the central portion being bored out smooth, to admit of the plug B being fitted to slide freely up or down.

A piece of pipe, C, having a shoulder, *c*, is screwed

into the stock A, to form a stop for the slide B at the bottom.

In the central portion of the stock A are fitted one or more spurs or cutting-tools, *a*, which slide in and out, and are operated by a wedge-shaped groove, *b*, in the slide B.

At various points opposite or in a line with the cutter *a*, are placed friction-rollers or studs, *e e*, to hold the stock centrally in the tube or casing while it is being cut.

To the upper end of the tool-stock A is screwed in tubing D, to extend up to the top of the well, by which the apparatus is rotated.

Through the tube D is a small tube or rod, E, connected with the sliding plug B, by which means the cutter *a* is forced out as it progresses in cutting the casing in the well.

The operation is as follows:

When it is desirable to remove the casing of an oil-well, the cutting apparatus is put down to the required depth inside the casing, and held in position by a dog or clamp secured to the tube D, and resting on the top of the well. Then put down the small pipe or rod E, and connect with the slide B. Then, by raising the slide, while turning the tube D, the casing is soon cut, so as to relieve them from the seed-bag water-packer or other obstructions.

What I claim as my invention, and desire to secure by Letters Patent, is—

The improved device herein described, consisting of the stock A and cutter *a*, the plug B, with its inclined groove *b*, the pipe C, and shoulder *c*, forming a step for the sliding plug B, the upper tubing D, and the connecting-tube or rod E, to extend to the top of the well, all constructed and arranged to operate substantially as set forth.

In testimony whereof I hereunto subscribe my name in the presence of—

PERLEY H. LAWRENCE.
